SPRAYING DEVICE

William Martin Vogel, Bloomfield, N. J.

Application July 19, 1938, Serial No. 220,041

5 Claims. (Cl. 299—88)

This invention relates to an improvement in spraying devices, and more particularly to the type utilized for the spraying of liquid insecticide or similar material.

In most devices of this character, a siphon tube, leading from a source of liquid supply, such as a tank or receptacle, is provided with an open end located close to the air blast opening at the end of the piston chamber or cylinder, and as a blast of air is directed through the opening it creates suction tending to draw the liquid through the siphon tube and distribute it in a fine spray or mist. The object of the present invention is to improve this known type of structure; to improve the spraying results; to provide a device in which the possibility of the spraying and air blast openings becoming clogged with dirt or foreign matter is greatly minimized and to otherwise simplify and improve the general structure of the device.

In the accompanying drawing wherein an embodiment of the invention is shown, Fig. 1 is a sectional view through a portion of a spraying device made in accordance with the invention; Fig. 2 is a front view of the nozzle portion of the invention; and Fig. 3 is a sectional view on the line 3—3 of Fig. 1, looking in the direction of the arrows.

In the drawing 1 indicates the piston chamber of the sprayer, the same being of cylindrical form, and generally composed of a rolled-up section of sheet metal having its longitudinal edges seamed together. Mounted for reciprocation within the cylinder 1 is a piston 2 of conventional construction, the same being fastened to one end of a piston rod 3 which extends out of the rear end of piston chamber, usually through an opening formed in a plug located at that end. The projecting end of rod 3 terminates in a handle, not shown, to enable the piston to be reciprocated in the manner well known in sprayer construction.

The forward end of the cylinder 1 is closed by a cap member 6 having its marginal edge seamed as at 7 to the end of cylinder 1, said cap being formed with a forwardly extending cylindrical cup portion 17 having a front end or wall 5 provided with an annular depression 8 which surrounds a spray opening 9. Fitted within the cap member 6 and held therein by frictional fit or by any other suitable method is a cup-shaped member or inner cap 10 provided with a forwardly extending nose 11 of a diameter less than the internal diameter of the cylindrical cup portion 17 so that an annular chamber 14 is formed within the cup-shaped member 17 between the inner

face thereof and the protruding nose portion 11 of member 10. Entering into this chamber 14 is a siphon tube 16 which extends upwardly from the liquid supply tank 4 secured to cylinder 1 in the conventional manner.

The nose portion 11 of cup 10 has its front wall 18 formed with an air blast opening 13 preferably located in alignment with spray opening 9. As a matter of fact, it is desirable to form the aligned openings 9 and 13 simultaneously and this can be done by a blow from a conical punch driven through the front wall 5 of member 17 and the front wall of the nose 11. Such an operation simultaneously produces the spray opening 9 and the aligned air blast opening 13, the spray opening 9 being of larger diameter than the air blast opening 13.

It is desirable that the space 15 between the front wall 18 of the nose 11 and the front wall 5 of member 17 be definite and of unvarying size and of less width than that of chamber 14, whereby the amount of liquid ejected out of the spray opening will be regulated. The fixed spacing of the two walls on the members 11 and 17 is governed by means of stops 12 pressed out of the front wall of the nose 11, these stops being spaced protuberances abutting against the rear face of the front wall 5, as clearly seen in Fig. 1. Thus, when the cup-shaped member 11 is pressed or otherwise secured in position within the member 17, the stops or abutments 12 on the front of the nose portion 11 coming in contact with the rear face of the front wall 5 limit the extent to which the cup 11 may be forced within member 17 and at the same time act to positively space the front wall of the nose 11 from the wall 5 of member 17 to thereby regulate the amount of liquid to be fed through spray opening 9. Also, when the aligned holes 9 and 13 are punched, the walls 5 and 18 are held apart in fixed, spaced relation by said stops 12.

With the arrangement disclosed, it has been found that upon reciprocation of the piston, the spray will be forced out of a spray opening 9 in the form of a finely diffused mist, most desirable in spraying operations. A swirling action of the air and liquid occurs in the annular chamber 14 as air is directed into the chamber from the cylinder through air blast opening 13. Such action has been found to prevent clogging of the openings 9 and 13 by dirt and other foreign matter, as any dirt tending to collect in or around the openings is driven off by the action of the air and liquid in chamber 14 and in the space 15, so that the spraying operation is always effective.

and the air blast and spray openings 9 and 13 seldom, if ever, require cleaning out.

While I have shown and described one embodiment of the invention, it is obvious that the same may be modified in various ways without departing from the spirit of the invention. For example, while I have shown a sprayer of the intermittent type, it will be understood however, that by utilizing the concentric arrangement of piston chamber and air compression chamber and other elements shown in my previous Patent No. 2,054,106, dated September 15, 1936, an extremely satisfactory type of so-called continuous sprayer is ideal for employment in connection with the type of continuous sprayer described in said patent.

What I claim is:

1. A sprayer having an air cylinder provided with a cupped closure cap at one of its ends, said cap having a substantially flat front wall provided with a spray opening, an inner cap located within and enclosed by the closure cap, said inner cap having a nose portion extending within the closure cap and approaching the front wall of the closure cap, said nose portion formed with a wall spaced from the front end wall of the closure cap, the nose portion of the inner cap being provided with an air blast opening in its end wall, and means located between the end wall of the nose portion and the front wall of the closure cap for holding these walls in definite spaced relation.

2. A sprayer having an air cylinder provided with a cupped closure cap at one of its ends, said cap having a substantially flat front end wall provided with a central spray opening, an inner cap located within the closure cap, said inner cap having a nose portion extending within the closure cap, said nose portion having an air blast opening aligned with the spray opening, the air blast opening being of less diameter than the spray opening, the nose portion having an end wall in which said air blast opening is formed, said end wall being spaced from the front end wall of the closure cap, the front end wall of the nose portion being formed with several spaced projections located in abutment with the front end wall of the cap by which definite spacing of the front wall of the nose portion from the front wall of the closure cap is maintained and the air blast opening and spray opening are maintained in fixed spaced relation.

3. A sprayer having an air cylinder provided with a cupped closure cap at one end, said cap

having a substantially flat front end wall provided with a spray opening, an inner cap located within the closure cap and provided with a nose portion formed with an air blast opening aligned with the spray opening, the nose portion having an end wall located near but spaced from the front end of the closure cap, the conformation of the nose portion within the closure cap being such as to co-operate with the closure cap to form an annular chamber within the closure cap around the nose portion, the spacing of the end wall of the nose portion from the front end wall of the closure cap being less than the width of the annular chamber.

4. A sprayer having an air cylinder provided with a cup-shaped closure cap at one end, said cap having a relatively flat front wall, an inner cap fitted within the outer cap, the inner cap having a projecting nose portion formed with a front wall located near but spaced from the rear face of the front wall of the closure cap, said front wall of the nose portion being formed with a plurality of protuberances located in abutment with the rear face of the front wall of the cap to thereby space the front wall of the nose portion a predetermined distance from the rear face of the front wall of the closure cap, aligned openings of different size in the two caps, the larger of said openings being formed in the closure cap and the smaller opening in the nose portion of the inner cap, and a siphon tube leading into the closure cap between the same and the nose portion of the inner cap.

5. A sprayer having an air cylinder provided with a cup-shaped closure cap at one end, said cap having a substantially flat end wall, an inner cap fitted within the closure cap, the inner cap being provided with a projecting nose portion having its forward end formed with a relatively flat end wall, said nose portion extending within the closure cap and having its end wall located close to and substantially parallel with the end wall of the closure cap, the end wall of the nose portion being provided with spaced projections extending forwardly and into the space between the two end walls and abutting against the rear face of the end wall of the closure cap to thereby limit the extent of projection of the nose portion toward the front end of the cap and to definitely regulate the distance between the two end walls, the two end walls having co-operating spraying openings.

WILLIAM MARTIN VOGEL.
